FIG. 1.

FIG. 6.

FIG. 2.

FIG. 3.

FIG. 4.

FIG. 5.

FIG. 7.

FIG. 8.

INVENTOR
FRANK R. PERRY.

Figure 1 is a front elevational view of a spoon showing my new design;

Figure 2 is a rear elevational view of the spoon;

Figures 3, 4 and 5 are sections on the respective lines 3—3, 4—4 and 5—5 of Figure 1;

Figure 6 is a side elevation view of the spoon;

Figure 7 is an enlarged fragmentary front elevational view showing the ornamental detail at the base of the spoon handle; and

Figure 8 is a similar enlarged rear elevational view showing the ornamental detail at the base of the spoon handle.

The essential features of my design for a spoon or

similar article reside in the configuration of the handle in combination with the particular ornamentation applied thereto.

I claim:

The ornamental design for a spoon or similar article, substantially as shown and described.
